UNITED STATES PATENT OFFICE

FRANK C. DELL, OF CHICAGO, ILLINOIS, ASSIGNOR TO AUTOPOINT COMPANY, OF CHICAGO, ILLINOIS, A CORPORATION OF ILLINOIS

ADJUSTABLE PEN SUPPORT

Application filed June 23, 1930. Serial No. 463,052.

My invention relates to fountain pens and the like and more particularly to means for supporting the same on a desk available for immediate use, commonly known as desk pen supports.

Pen supporting devices adapted to support the pen in a vertical or semi-vertical position, and permitting rotation about a central axis are common in the trade, but such devices generally have objectionable features, the most important relating to the simplicity of the parts, ease in assembly and adjustment of the parts, and economy of manufacture.

In addition another common objection relates to the ease of movement of the pen in the holder to any desired position without undue effort. Generally the pen support is assembled and adjusted at the factory and after reasonable use the device rotates either too tightly or too loosely and the proper use thereof is seriously hampered.

An object of my invention is to provide a pen support that is capable of movement in any direction around a pivot, a support that is relatively economical to manufacture due to the few parts, and a further object is to provide means carried by the disc for providing frictional adjustment of the movement in either a vertical or horizontal plane.

A further object of my invention is to provide a holder associated with swivel means whereby a pen may rest in a horizontal position at any point about the circumference of the pivot. Thus the pen is available for use from any angular position about the pivot.

The invention will be more readily understood by reference to the accompanying drawings in which,

Fig. 1 is a side elevation of a pen support construction in accordance with my invention;

Fig. 2 is a fragmentary vertical section elevation of the device shown in Fig. 1;

Fig. 3 is a vertical sectional view on the lines 3—3 of Fig. 1;

Fig. 4 is a side elevation of a modified form;

Fig. 5 is an end elevation of the same; Fig. 6 is a side elevation of another modified form; and

Fig. 7 is an end elevation of the same. By reference to the drawings, it will be seen that my preferred form shown in Figs. 1, 2 and 3 comprises a collar 10, having a central threaded aperture therein for the reception of the threaded bolt 11 passing through the washer 12 on the under side of the base 13. Formed on the upper side of the collar 10 is the post 14 having an annular circumferential groove 15 therein at a suitable predetermined distance from the bottom thereof. This post 14 may preferably be formed at a point on the collar 10 away from the geometrical center thereof, for a purpose to be later described, or the post may be formed at the geometrical center as desired.

Socketed over the post 14 is the split disc 16 having a vertically formed aperture therein adapted to receive the post 14. The disc is split through a portion of the diameter to provide for expansion and to insure a tight fit over the post 14. The disc 16 is also provided with a central aperture which registers with the groove 15 in the post when the disc is placed thereover and forced down to proper distance.

The socket member 17 is formed with a threaded stem 18 to which is attached the pen holder 19 of suitable form carrying the pen 20. The lower portion of the socket member is formed to provide the semi-spherical wings 21, 22 having their inner faces flat and parallel and adapted to frictionally contact the sides of the disc 16. The wings 22, 21 are also provided with central apertures which register with the aperture in the disc, and the groove 15 on the post 14. The screw 23 is inserted in the registering apertures and cooperates with threads on one of the wings 21, 22, thus binding the parts.

Obviously therefore, the assembly is locked by the insertion of the screw 23 engaging the groove 15, and the parts cannot be separated. In addition, by the tightening of the screw 23 the wings 21, 22 of the

socket member are not only more tightly pressed to the sides of the disk 16, but the split disc is caused to contract also, thus causing greater friction around the post 14.

5 Thus, by a single adjustment of the screw 23 both the vertical and horizontal swivel movements may be adjusted. Thus the form described enables the use of the device at any angular position; the socket member 10 moves in a vertical plane and the disc moves in a horizontal plane about the post 14. By this construction the pen and carrier may be rested flat upon the base, if desired at any point about the pivot.

15 By reason of the post being displaced from the center of the collar 10, the device will appear to be centrally supported and presents a more satisfactory appearance, although obviously the post may be centrally

20 formed on the collar 10.

The construction shown in Figs. 4 and 5 is a modification of the inside or disc portion of the device shown in Figs. 1 and 2 and 3. In this form, a threaded post 24 is 25 provided having a base contacting collar 25 near the upper end, and an annular groove 26 formed near the upper extremity. The disc 27 is provided with an upwardly disposed recess into which the post 24 is adapted 30 ed to be inserted. The post being inserted within the opening in the disc, the metal in the side of the disc is displaced as by a prick punch 28 on one or both sides of the disc as desired, forcing the metal of the disc ad-

35 jacent the groove 26 into the groove thus providing an additional friction and locking the disc and post together and preventing the separation thereof. The disc is provided with a central aperture 29 thus adapt- 40 ing this construction for use with the socket member construction heretofore described. Obviously, the displacement of the metal at 28 is not intended to bind the parts, but permits a non-separable rotation of the disc on 45 the post.

The construction shown in Figs. 6 and 7 is a further modification of the form shown in Figs. 4 and 5.

In this form, I provide a threaded post 30 50 having the collar 31 formed thereon and adapted to rest on the top of a base (not shown). At the upper end of the post I provide the annular groove 32. The grooved portion of the post 30 is adapted to 55 be inserted a suitable distance within the split disc 33 having a vertically disposed recess of sufficient length. At the lower portion of the disc 33 I provide a threaded aperture through which I insert the adjusting screw 34. This aperture is formed to 60 register with the groove 31 in the post, and thus when the screw 34 is inserted into the aperture, it serves to prevent the separation of the disc from the post. In addition, the 65 tightening of the screw 34 tends to tighten

the split disc, thus increasing the friction around the post 30.

The split disc 33 is also provided with a central aperture so that this portion of the device may be used with the socket member 70 construction heretofore described.

Thus it will be seen that my invention has provided a pen support permitting the support of a pen at any angle from the horizontal, and at any point about a pivot, and which has the advantage of simple and efficient adjustment to suit the particular need of the user, and with a minimum of parts, simply manufactured and assembled.

Modifications may be made in the device 80 herein disclosed within the skill of the mechanic and I do not wish to be limited except as indicated in the appended claims.

I claim:

1. In combination, a support, a post fixed 85 therein, said post having a circumferential groove between its ends, a disc having a side recess adapted to receive the post, a pen support comprising a socket and a wing that are operatively related to said disc, and rotatable relative thereto, and means carried by the disc and entering the groove in the post preventing removal of the disc and permitting angular movement of the disc on the 90 post.

2. In combination, a support, a post fixed 95 therein, said post having a circumferential groove between its ends, a disc having a side recess adapted to receive the post, said disc being slit along a portion of its periphery whereby to insure frictional contact with said post, a pen support comprising a socket and a wing that are operatively related to said disc and rotatable relative thereto, and means carried by the disc and entering the groove in the post preventing removal of the disc and permitting angular movement of the disc on the 100 post.

3. In combination a support, a post fixed 110 therein, said post having a circumferential groove between its ends, a disc having a side recess adapted to receive the post, a pen support comprising a socket and a pair of parallel wings adapted to frictionally engage the faces of said disc and to be operatively 115 related and rotatable relative thereto, and means carried by said disc and entering the groove in the post whereby to prevent the removal of the disc, and permitting angular movement of the disc on said post.

4. In combination a support, a post fixed 120 therein, said post having a circumferential groove between its ends, a disc having a side recess adapted to receive the post, a pen support comprising a socket and a wing that are operatively related to said disc and rotatable relative thereto, said disc having an aperture which registers with the groove 125 on said post, and a threaded screw carried by said disc and entering the groove in the 130

post whereby to prevent the removal of the disc, and permitting angular movement of the disc on said post.

5. In combination a support, a post fixed therein, said post having a circumferential groove between its ends, a disc having a side recess adapted to receive the post, a pen support comprising a socket and a pair of relatively resilient wings that are operatively related to said disc and rotatable relative thereto, said disc having an aperture which registers with the groove on said post, and a threaded screw carried by said disc and entering the groove in the post whereby to prevent the removal of the disc, and permitting angular movement of the disc on said post.

6. In combination, a support, a post fixed therein, said post having a circumferential groove between its ends, a disc having a side recess adapted to receive and frictionally engage the post, a pen support comprising a pen socket and a pair of relatively resilient, parallel wings, said wings being operatively related to said disc and rotatable relative thereto, and means provided by the displacement of a portion of the metal in said disc adjacent to the ultimate position of the groove therein preventing removal of the disc from the post and permitting angular movement of the disc thereon.

7. In combination, a support, a post fixed therein, said post having a circumferential groove between its ends, a disc having a side recess adapted to receive the post, a pen support comprising a socket and a pair of relatively resilient wings that are operatively related to said disc and rotatable relative thereto, said disc having an aperture which registers with the groove on said post, and a threaded screw carried by said disc and entering the groove in the post whereby to prevent the removal of the disc, and permitting angular movement of the disc on said post, said disc and said wings being formed to present a substantially spherical appearance when operatively associated.

50 8. In combination, a support, a post fixed therein, said post having a circumferential groove between its ends, a disc having a side recess adapted to receive and frictionally engage the post, a pen support comprising a pen socket and a pair of relatively resilient, parallel wings, said wings being operatively related to said disc and rotatable relative thereto, and means provided by the displacement of a portion of the metal in said disc adjacent to the ultimate position of the groove therein preventing removal of the disc from the post and permitting angular movement of the disc thereon, said disc and said wings being formed to present a sub-

stantially spherical appearance when operatively associated.

9. A pen support adapted to provide swivel movement, comprising an upstanding post, a disc having a recess therein adapted to receive said post, a pen socket member, said socket member comprising a pen holder and a wing joined thereto, said wing being adapted to fit over the side of said disc, and means carried by said disc for preventing the separation of the parts.

10. A pen support adapted to permit free rotation about a pivot, comprising in combination an upstanding post having a circumferential annular groove near the upper extremity thereof, a disc having a recess therein adapted to frictionally engage said post, a socket member comprising a pen holder and a pair of parallel wings, said wings being adapted to frictionally engage the sides of said disc and means carried by said disc for preventing the separation of the parts.

11. A pen support adapted to provide swivel movement, comprising an upstanding post, a disc having a recess therein adapted to receive said post, a pen socket member, said socket member comprising a pen holder and wing joined thereto, said wing being adapted to fit over the side of said disc, said disc and said wing having registering central apertures, and a single screw passing through said central apertures for preventing the separation of the parts.

12. A pen support adapted to provide swivel movement, comprising an upstanding post, a disc having a recess therein adapted to receive said post, a pen socket member, said socket member comprising a pen holder and wing joined thereto, said wing being adapted to fit over the side of said disc, said disc and said wing having registering central apertures and said groove on said post also registering with said central apertures, and a single screw passing through said central apertures for preventing the separation of the parts.

13. A pen support adapted to permit free rotation about a pivot, comprising in combination an upstanding post having a circumferential annular groove near the upper extremity thereof, a split disc having a recess therein adapted to frictionally engage said post, a socket member comprising a pen holder and a pair of parallel wings, said wings being adapted to frictionally engage the sides of said disk, and means carried by said disc for preventing the separation of the parts, said means also serving to provide adjustment of the frictional contact of the wings and the disk, and the disk and the post.

14. A swivel type fountain pen support comprising in combination, an upstanding post having a circumferential annular groove

therein near the upper extremity thereof, a disc having a recess extending inwardly from the periphery thereof, means carried by said disc preventing the separation of 5 the post therefrom but permitting rotation of the disc therearound, a socket member comprising a pen socket terminating in a pair of parallel wings, said wings being adapted to frictionally engage the faces of 10 said disc, and a single screw passing through said wings and disc for preventing the separation of the parts.

In testimony whereof I have affixed my signature.
